UNITED STATES PATENT OFFICE.

WILLIAM P. PARSONS, OF CORNING, NEW YORK, ASSIGNOR TO CORNING GLASS WORKS,
OF CORNING, NEW YORK, A CORPORATION OF NEW YORK.

DESIGN FOR A GLASS GRADUATE.

Application filed November 8, 1923. Serial No. 7,719. Term of patent 14 years.

To all whom it may concern:

Be it known that I, WILLIAM P. PARSONS, a citizen of the United States, residing at Corning, in the county of Steuben and State of New York, have invented a new, original, and ornamental Design for a Glass Graduate, of which the following is a specification, reference being had to the accompanying

drawings, forming part thereof, wherein—

Figure 1 is a plan view, and

Fig. 2 is a side elevation, of a glass graduate, showing my new design.

I claim:—

The ornamental design for a glass graduate, as shown.

WILLIAM P. PARSONS.
